SHIP FORM

Leone Costa, Canido-Vigo, Spain, assignor to
W. K. Maier, New York, N. Y.

Application February 25, 1948, Serial No. 10,709
In Germany January 24, 1941

Section 1, Public Law 690, August 8, 1946
Patent expires January 24, 1961

3 Claims. (Cl. 114—56)

1

My invention relates to ships, and more especially to the outer form of the fore part of ocean-going merchantmen having Froude numbers

$$v/\sqrt{lg} = 0.2 \text{ to } 0.3$$

wherein v indicates the speed of the ship in m./sec., l indicates the length of the ship in meters, and g indicates the gravity in m./sec. 2.

A main object of the invention is to provide a ship form which affords a small resistance and economic propulsion in smooth water as well as in rough sea, so that a high average speed of the ship is secured under all conditions.

The invention is diagrammatically illustrated in the accompanying drawing.

Fig. 1 is a bow elevation of a ship's form according to the invention, and

Fig. 2 is a side elevation of Fig. 1.

In Figs. 1 and 2, the sections of the under-water construction of the ship's fore body extending over about 20% of the total length of the ship from the stem to the region of the first trough of the ship's wave system are determined by the direction of radii drawn from a common centre I (cf. e. g. Patent 1,736,315). The radii from the centre I determine the form of the under-water frames identified by the letter U (with the exception of their roots) at least up to the water line. Above this line they are continued by transition parts identified by the letter T which connects the under-water frames with the more inclined above-water frames identified by the letter D. The range of these transition parts is confined below by the constructional water line CWL and above by a straight line b forming an angle α of about 7° with the CWL and intersecting the latter at a distance d of about 20% of the total ship length from the stem.

The substantially straight frame sections of the dead work above the line b form an angle of at least 25° with the center line xy , i. e. an angle of at least 50° measuring the flare between both sides of the dead work, whilst all under water frames (even the most inclined Nos. 16 and 17) are at an essentially smaller angle to this center line xy . The frames of the dead work may be determined by the direction of radii drawn from a common centre II. According to the embodiment shown in the drawing, this centre II is situated farther from the centre line xy , and closer to the bottom line xz , than centre I. Alternatively, the frame sections above water may be arranged about parallel to one another or according to any other scheme. Though the frame sections lying above and under water, respectively,

2

are preferably straight, they may be a little curved. At any rate, their transition into the side and bottom lines, respectively, is effected, as usually, by gradual bending.

5 The transition parts of the frames confined by the CWL and the line b must not necessarily be curved over their whole length but may also be composed of substantially straight frame parts, the angle of which relative to the center line xy is considerably greater than that of the frame parts under water but smaller than that of the frames above.

Even if the under-water frames are very steeply arranged, the invention permits of hydrodynamically satisfactory transitions to great dead work frame angles of e. g. 90° to 100° measuring the flare between both sides. Thus, the fore part of a ship's hull may be given an optimum form with regard to flow towards the screw, wake distribution, and propulsion. Whilst the natural development of the bow wave is influenced as little as possible, the downward movements of the fore-peak in rough weather are strongly braked.

The ship's aft-body may be designed in any suitable manner.

If desired, the underwater frames may extend upwardly somewhat above the CWL, and the transition parts connecting the under-water frames with the above-water frames may start 30 at a point between the CWL and the line b . Furthermore, if desired, the above-water frames may extend downwardly somewhat below the line b , and said transition parts may reach only up to a point somewhat below said line b .

35 It is understood that the drawings illustrate the invention merely by way of example. In any case, whether the frame sections of the dead work frame above the line b are determined by the direction of radii drawn from a common center II as shown in the drawing or whether the frame sections of the dead work are arranged substantially parallel to each other or in any other manner as mentioned above, they are inclined to the center line $x-y$ at angles which are larger than the angles of the underwater frames. According to the invention, the transition parts connecting the frame sections of the dead work frame with the underwater frames are arranged in the range determined by the CWL and the line b .

50 What I claim is:

1. In the construction of the forepart of a ship's hull; a frame, including a plurality of underwater frame sections, a plurality of dead work frame sections and a plurality of transition parts interconnecting said underwater frame sec-

tions and said dead work frame sections, said underwater frame sections being disposed in the direction of radii drawn from a common center below the bottom line and forming angles of less than 50°, said dead work frame sections being disposed in the direction of radii drawn from a common center below the bottom line and forming angles greater than 50°, said underwater frame sections extending upwardly substantially to the constructional water line, said dead work frame sections extending downwardly substantially to a line intersecting the constructional water line at a distance of about 20% of the total length of the ship from the stem and upwardly inclined from said point of intersection towards the stem at an angle of approximately 7°, and said transition parts being disposed in the zone defined by the constructional water line and the upwardly inclined intersecting line of aforesaid and connecting the upper end of the underwater frame sections and the lower end of the dead work frame sections.

2. In the construction of the forepart of a ship's hull; a frame, including a plurality of underwater frame sections, a plurality of dead work frame sections and a plurality of transition parts interconnecting said underwater frame sections and said dead work frame sections, said underwater frame sections being disposed in the direction of radii drawn from a first common center below the bottom line and forming angles of less than 50°, said dead work frame sections being disposed in the direction of radii drawn from a second common center further away from the vertical center line of said hull than the first common center and closer to the bottom line of said hull than the first common center and forming angles greater than 50°, said underwater frame sections extending upwardly substantially to the constructional water line, said dead work frame sections extending downwardly substantially to a line intersecting the constructional water line at a distance of about 20% of the total length of the ship from the stem and extending upwardly from said point of intersection towards the stem at an angle of approximately 7°, and said transition parts being disposed in the zone

defined by the constructional water line and the intersecting line aforesaid and connecting the upper end of the underwater frame sections and the lower end of the dead work frame sections.

3. In the construction of the forepart of a ship's hull; a frame, including a plurality of underwater frame sections, a plurality of dead work frame sections and a plurality of transition parts interconnecting said underwater frame sections and said dead work frame sections, said underwater frame sections being disposed in the direction of radii drawn from a common center below the bottom line and forming angles of less than 50°, said dead work frame sections being disposed in the direction of radii drawn from a common center below the bottom line and forming angles greater than 50°, said underwater frame sections extending upwardly substantially to the constructional water line, said dead work frame sections extending downwardly substantially to a line intersecting the constructional water line at a distance of about 20% of the total length of the ship from the stem and upwardly inclined from said point of intersection towards the stem of the ship, said transition parts being disposed in the zone defined by a triangle, including as its sides the constructional water line, the stem of the ship, and the inclined line aforesaid, said inclined line being the longest dimension of said triangle, said transition parts connecting the upper end of the underwater frame sections and the lower end of the dead work frame sections.
